METHOD OF AND APPARATUS FOR
CONDITIONING AIRClarence L. Ringquist, La Crosse, Wis., assignor
to The Trane Company, La Crosse, Wis.

Application January 15, 1947, Serial No. 722,244

8 Claims. (Cl. 62—6)

1

This invention relates to an air conditioning apparatus, or system, particularly adapted to condition the air in a room to a predetermined dew point and to provide for the addition of a predetermined amount of outside air for ventilation, with means for regulating the amount of moisture in the outside air.

One object of my invention is to introduce into the room a predetermined amount of outside air for ventilation purposes and to prevent the introduction of varying amounts of outside air.

Another object of my invention is to treat the outside air separately and reduce it to a predetermined dew point before mixing it with recirculated or room air.

Another object of my invention is to provide a novel cooling means for dehumidifying the air before mixing it with the recirculated air; which will be at a different dew point than the outside air.

Another object of my invention is to provide means for conditioning the recirculated air, to provide a predetermined dew point, and to provide means for conditioning the outside air to a different dew point and mixing the recirculated air and outside air in predetermined amounts to secure a third dew point below a predetermined point.

The above and other objects of my invention will be apparent in the following specification and drawings, wherein:

Fig. 1 shows diagrammatically the apparatus used in my invention.

Fig. 2 shows an end view of the longitudinal heat exchanger.

Fig. 3 shows a cross sectional view of the longitudinal heat exchanger.

Referring to Fig. 1, 25 represents the room or space to be conditioned, wherein outside air is drawn into the inlet 26 by means of a fan 12 which is of a squirrel cage variety, and which draws outside air into the apparatus in a predetermined amount; and the outside air is then passed through a longitudinal fin coil 24, a cross-section of one of the elements 48 of which is shown in Fig. 2.

The apparatus comprises a casing composed of side walls 28, top wall 29, bottom wall 30, with a front wall not shown.

In the top of the casing there are outlets 14 through which fans 16 draw the air from the mixing chamber 15 where the recirculated air and the outside air is mixed before entering into the room.

The fans 16 are operated by a motor 17, through

2

the pulley 18, belt 19, pulley 20, attached to shaft 21, on which are mounted fans 12 and 16.

The recirculated air is pulled from the room 25 into the apparatus through the coil 22, through inlet 34, and emits from the coil 22 into the mixing chamber 15, where it mixes with the outside air which enters the coil 24 at 47 and leaves the coil 24 at 23.

Referring to Fig. 2 and Fig. 3 an element 48 of the longitudinal fin coil 24 is shown as composed of a longitudinal casing 43, with a conduit therein 44, for the flow of heat exchange fluid, and between the casing 43 and the conduit 44 are interposed heat exchange fins 46 which provide air passages 45 between the casing 43 and the conduit 44.

The outside or ventilating air is drawn into the unit through the opening 26, communicating with the outside air, and the amount of air is controlled by a damper 27 together with the fan 12 which handles a predetermined amount of air.

The outside air then is passed through the dehumidifying coil 24 and emits into the mixing chamber 15 where it is mixed with the recirculated air which enters the unit through the inlet 34 and passes through the coil 22.

The coil 22 is supplied with heat exchange medium from the pipe 35, in which there is interposed a valve 38, controlling the supply of the heat exchange medium to the coil 22.

The valve 38 is controlled by a dry bulb thermostat 39 through the line 40 so that the amount of work performed by the coil 22 will be responsive to the dry bulb temperature in the room 25. When the temperature in the room 25 drops below a predetermined temperature, the thermostat 39 causes the valve 38 to open, and the heat exchange medium from pipe 35 by-passes the coil 22 and leaves the apparatus through return pipe 36.

The coil 24 is supplied with heat exchange fluid from the pipe 31. Connected with the pipe 31 is a by-pass pipe 42 which connects with a pipe 35 which is connected with the valve 38 and the pipe 31. Interposed in the by-pass 42 is a valve 32 which is responsive to a humidostat 33 situated in the room 25, which humidostat, through a line 41, will control the operation of the valve 32 which controls the amount of flow of heat exchange fluid through the coil 24 because when the valve is open the flow will be through the by-pass instead of through the coil; thus the amount of work performed by the coil 24 is controlled responsive to the amount of moisture in the room 25. So that in effect, the coil 24 will remove from the outside air sufficient moisture

so that when mixed with the recirculated air the latent load requirements will be satisfied.

Assuming that the ventilation requirements of three people in the room are 199.8 lbs. per hour of outside air, and it is desired to maintain the inside air conditioned at 80° dry bulb and 67° wet bulb, it is apparent that there are required to be removed from the recirculated air the moisture equivalent to the latent load of the people in the room, and that there will also be required to be removed from the outside air a predetermined amount of moisture as to enable the mixture to meet the required moisture requirements.

The former air conditioning systems have been directed to mixing the outside air and the recirculated air and then conditioning the mixture, and due to the variations in the amount of moisture in the outside air, it has been found that this is impractical and the results were unsatisfactory amounts of moisture in the resultant air due to the varying amounts of moisture in the outside air, consequently the apparatus and method disclosed in this invention is directed to conditioning the outside or ventilating air to such a predetermined moisture content as will take care of the assumed latent load in the room and further to condition the recirculated air substantially without the removal of moisture but to remove a sensible heat therefrom so that when the recirculated air is combined with the outside air the

room would be 78—2.05=75.95 grs. of moisture per pound of air leaving the unit.

In the invention disclosed, all of the removal of moisture is done by the outside or ventilating air, thus

$$\frac{3510 \text{ (grs. per hr. to be removed)}}{199.8 \text{ (amount of outside air)}} = 17.8 \text{ grains}$$

per pound of air to be removed to maintain a predetermined moisture content of 78 grains per pound.

78 grs.—17.8 grs.=60.2 grs. per pound which corresponds to the moisture content per pound of air with 53° dew point. Thus, the outside air leaving the coil 24, at 23, must have a temperature of 53° saturated. Inasmuch as this leaving temperature of the outside air is lower than the temperature of the recirculated air, it is evident that the outside air will remove a small amount 20 of sensible heat from the recirculated air.

The sensible heat available for cooling below the predetermined dry bulb is then—

199.8 (lbs. of air for ventilation) $\times 0.24$ (specific heat of air) $\times 80^\circ$ (predetermined D. B. temp.) — 25 53° (leaving temp. of ventilated air)=1280 B. t. u. per hour, subtracting this amount 1280 B. t. u. from 8250 (total B. t. u. sensible load)= 6970 B. t. u. per hr. load to be removed by the recirculated air when passing through the recirculated air coil, and

6970 B. t. u. per hr. to be removed by recirculated air coil

$$0.24 \text{ (specific heat of air)} \times 1730 \text{ (lbs. of air to be emitted into room)} - 199.8 \text{ lbs. of ventilated air} = 19^\circ$$

resultant air will have a predetermined dry bulb. For example: assume a typical office space with dimensions 14' x 16' x 11' high and exposed by two sides and roof, with three occupants, and with the outside air at 95° dry bulb, 78° wet bulb, containing 116 grains of moisture per pound of air and a desired inside air condition of 80° dry bulb, 67° wet bulb and containing 78 grains per pound of air. According to engineering data there would be a sensible heat gain of 6000 B. t. u. due to transmission losses and 2250 B. t. u. due to internal heat additions from lights and people, or a total of 8250 B. t. u. heat gain. Also, according to engineering data, an internal latent load of 525 B. t. u. due to people.

The ventilation requirements for three people at the rate of 15 C. F. M. per person would be 45 C. F. M., which is equal to 199.8 pounds of air per hour. A further assumption is the dry bulb temperature of the mixed air entering the room should not be lower than 60°.

8250 (sensible load in B. t. u.)

$$0.24 \text{ (specific heat of air)} \times 80 \text{ (desired temp.)} - 60 \text{ (leaving temp.)} = 1730 \text{ pounds of air per hour}$$

which is the total amount of sensible cooling performed by the mixed outside and recirculated air. The other equation referred to the latent load is:

$$\frac{525 \text{ B. T. U. (latent load)}}{1050 \text{ (latent heat of water)}} \times$$

$$7000 \text{ (gr. per lb.)} = 3510 \text{ grs. per hr.}$$

to be removed from the water on account of the latent load, and

3510

$$1730 \text{ lbs. of air per hr., emitted into room} = 2.05 \text{ gr. of moisture to be removed per pound of air on account of latent load.}$$

To maintain the desired moisture content of 78 grs. of moisture per pound of air in the room, the moisture content of the mixed air coming into the

35 temperature difference, and 80° (predetermined dry bulb air temperature) —19°=61° air leaving recirculated air coil, thus, 199.8 lbs. of ventilated air is mixed with 1529.2 lbs. recirculated air to obtain 1730 lbs. of air emitting from the unit into the room.

45 Mixing 1529.2 lbs. of recirculated air at 61° dry bulb and having moisture content of 78 grains per pound, with 199.8 lbs. of outside dehumidified air at 53° dry bulb temperature and with a moisture content of 60.2 grains per pound, produces a final condition of the mixture of 60.1° dry bulb temperature and a moisture content of 75.95 grains per pound, which will maintain in the room, conditioned air of 80° dry bulb and with a moisture content of 78 grains per pound.

55 Under the present type of units where the outside air and recirculated air are mixed before conditioning, mixing 199.8 lbs. of 95° dry bulb and 116 grains of moisture per pound outside air with 1529.2 pounds of 80° dry bulb and 78 grains of

60 moisture per pound results in a mixture of 81.4° dry bulb and 82.3 grains of moisture per pound, and from the coil curve this could be conditioned to 61° dry bulb with a moisture content of 75.95 grains of moisture per pound, which is the desired condition.

70 However, assume the outside conditions to vary so that the outside air drops to 85° dry bulb with 117 grains of moisture per lb. and the inside conditions to be maintained at 80° and 78 grains of moisture per pound as previously. The required dry bulb temperature of the mixed air to maintain 80° would be 69.8°, and the air mixture would be 199.8 pounds of 85° dry bulb air with 117 grains of moisture per pound and 1529.2 pounds of 80° dry bulb air with 78 grains of moisture per pound, resulting in a condition of 80.8° dry bulb with 82

grains of moisture per pound. In order to reduce this mixture to the desired moisture content of 75.95 grains per pound, it would be necessary to reduce the dry bulb temperature to 64° according to the coil curve, which is 5.8° below the dry bulb temperature necessary to maintain the desired temperature and would result in undercooling the room. Also, if the dry bulb temperature of the mixed air was reduced only to 69.8° then the moisture content would be 77 grains per pound, which would not be enough to absorb the latent load in the room and the humidity would be too high.

Assume the same conditions with the outside air taking care of the latent load as disclosed herein:

Heat gains are:

2000 Transmission   2250 Internal Sensible heat   525 latent   } according engineering data

The required dry bulb leaving temperature of the mixed air is 69.8° from the following equation—

$$\frac{4250 \text{ (sensible load B. t. u.)}}{1730 \text{ (lbs. of air, mixed)} \times 0.24 \text{ specific heat of air}} = 10.2^\circ$$

$$\text{and } 80^\circ - 10.2^\circ = 69.8^\circ$$

The desired moisture content is 78 grains per pound of air as before and to maintain this condition the mixed air must have a moisture content of 75.95 grains per pound, which is 2.05 grains per pound (the latent load) less than the desired moisture content of the room air.

The outside air is reduced to 53° saturated as before, resulting in a moisture content of the conditioned outside air of 60.2 grains per pound.

The sensible heat available for removal by outside air is 1280 B. t. u. The total sensible heat load of 4250 B. t. u. is therefore reduced by 1280 B. t. u. which leaves 2970 B. t. u. sensible heat to be removed by the recirculating coil. The temperature of the air leaving the recirculating coil would be 71.85° dry bulb as shown by the following equation:

$$\frac{2970}{0.24 \times (1730 - 199.8)} = 8.15^\circ$$

$80^{\circ} - 8.15^{\circ} = 71.85^{\circ}$ dry bulb, which will produce a mixture of 69.7° dry bulb with a moisture content of 75.95 grains per pound, which is the desired condition. It is obvious from the foregoing example that the method of having the outside or ventilating air take care of the latent load and the recirculated air regulating the dry bulb temperature, possesses distinct advantages over the method of mixing the outside air and recirculated air to a mixture which is then conditioned.

It is apparent from the foregoing that I have invented a new and novel means of conditioning the air in a room, set forth in the following claims, in which I claim:

1. A method of air conditioning a space comprising moving a predetermined amount of outside air in parallel fluid flow heat exchange relationship with a heat exchange fluid, moving air from said space into heat exchange relationship with a heat exchange fluid, then mixing said outside air and said air from the space, and moving the mixed air into the space.

2. A method of air conditioning a space comprising moving a heat exchange fluid through a first heat exchanger and then through a second heat exchanger, moving outside air into parallel

fluid flow heat exchange relationship with the heat exchange fluid in said first heat exchanger, moving air from said space into heat exchange relationship with the heat exchange fluid in said second heat exchanger, then mixing said outside air and said air from said space and then moving the mixed air into the space.

3. Apparatus for air conditioning a space comprising means for moving a predetermined amount of outside air in parallel fluid flow heat exchange relationship with a heat exchange fluid, means for moving air from said space into heat exchange relationship with a heat exchange fluid, means for mixing said outside air and said air from said space and means for moving the mixed air into the space.

4. Apparatus for air conditioning a space comprising a first heat exchanger having means for conducting heat exchange fluid and means for conducting air in heat exchange relationship with said means for conducting heat exchange fluid, said means for conducting heat exchange fluid and said means for conducting air being substantially parallel with each other, means for moving outside air through said means for conducting air, a second heat exchanger, means for moving air from said space through said second heat exchanger, means for mixing said outside air leaving the first heat exchanger with said air from said space leaving said second heat exchanger and means for moving the mixed air into the space.

5. Apparatus for air conditioning a space comprising a plurality of conduits for conducting a heat exchange fluid, a plurality of ducts with each duct surrounding one of said conduits and being of such a size as to provide a passageway for air between said duct and said conduit, heat transfer fins in said passageway, said fins extending longitudinally of the conduit and the duct, means for moving outside air through said ducts, a heat exchanger, means for moving air from said space through said heat exchanger, means for mixing said outside air leaving said ducts and said air from said space leaving said heat exchanger and means for moving the mixed air into the space.

6. Apparatus for air conditioning a space comprising a first heat exchanger having liquid conduits with a supply and a discharge opening and conduits for conducting air, said liquid conduits and said air conduits being constructed and arranged for parallel flow of liquid and air, a second heat exchanger, a conduit connected at one end 50 to the discharge opening of the conduit of said first heat exchanger and at the other end to said second heat exchanger for conducting liquid discharged from said first heat exchanger to said second heat exchanger, means for moving outside air through said first heat exchanger, means for moving air from said space through said second heat exchanger, means for mixing said outside air leaving said first heat exchanger and said air from said space leaving said second heat 55 exchanger and means for moving the mixed air into said space.

7. Apparatus for air conditioning a space comprising a first heat exchanger, a second heat exchanger, means for conducting a heat exchange fluid first through said first heat exchanger and then through said second heat exchanger, a first by-passing means for conducting the heat exchange fluid around said first heat exchanger, humidity responsive means in said space for controlling the operation of said first by-passing

means, a second by-passing means for conducting the heat exchange fluid around said second heat exchanger, a temperature responsive means in said space for controlling the operation of said second by-passing means, means for moving outside air through said first heat exchanger, means for moving air from said space through said second heat exchanger, means for mixing the air from said first heat exchanger with the air from said second heat exchanger and means for moving the mixed air into said space.

8. Apparatus for air conditioning a space comprising a casing having a first inlet opening for admitting outside air, a second inlet opening for admitting air from said space, a mixing chamber, and an outlet opening in the casing for discharging air from the mixing chamber into said space, a first heat exchanger having air ducts arranged to discharge air into said mixing chamber, a conduit leading from said first inlet opening to said first heat exchanger, a fan in said conduit for moving air in said conduit, a fan mounted in said mixing chamber at the outlet

10

15

20

opening for discharging air from said mixing chamber into said space, means mounting said fans on a common axis of rotation, a second heat exchanger at the second inlet opening, the second heat exchanger having air ducts arranged in a direction normal to the air ducts of said first heat exchanger to discharge air in a direction normal to the direction of the air stream from said first heat exchanger.
